UNITED STATES PATENT OFFICE.

WILLIAM H. HANKIN, JR., OF BROOKLYN, NEW YORK.

SAW.

SPECIFICATION forming part of Letters Patent No. 295,285, dated March 18, 1884.

Application filed January 7, 1884. (No model.)

To all whom it may concern:

Be it known that I, WILLIAM H. HANKIN, Jr., a citizen of the United States, residing at Brooklyn, E. D., in the county of Kings and State of New York, have invented new and useful Improvements in Saws, of which the following is a specification.

This invention has for its object to provide a simple, cheap, and efficient frame capable of receiving saw-blades of varying thickness, and of being bent to conform to the upper and lower edges of the wooden handle, and to provide a saw-blade of novel construction, whereby it is braced and steadied back of the butt-end of the frame carrying the handle, whereby the saw is nicely hung and evenly balanced, and a more extended toothed edge may be provided.

The objects of my invention I accomplish by the construction of parts hereinafter described and claimed, reference being had to the accompanying drawings, in which—

Figure 1 represents a side elevation of a hand-saw constructed according to my invention. Fig. 2 is an inverted plan of the same. Fig. 3 is a horizontal section in the plane $x x$, Fig. 1. Fig. 4 is a plan of the sheet-metal frame detached before the same is bent. Fig. 5 is a perspective view of the same when bent.

Similar letters indicate corresponding parts. In the drawings, the letter A designates the saw-blade, and B is the handle. The saw-blade is provided with a tail, C, from the back of which projects a spur, a.

D is a sheet-metal frame which serves to secure the blade to the handle. This sheet-metal frame consists of two flexible arms, b b', and two jaws, c c'. It is made of a flat strip of sheet metal, (see Fig. 4,) into which is punched a slot, d, and a series of holes, e e', f f', and g. After the strip has been thus prepared, the arm b is bent to conform to the top edge of the handle B. The arm b' is bent to conform to the bottom edge of the handle, and the jaws c c' are turned inward, (see Fig. 5,) so as to leave just room enough between them to admit the butt-end of the blade A. The flexible jaws c c' are then fastened to the blade by means of rivets h, passing through the holes f f', and the arms b b' are secured to the handle by screws i i', passing through the holes e e', respectively, while the spur a on the back of the tail C passes through

hole g and enters the body of the handle, as shown in Figs. 1 and 2.

I am aware that cast-metal frames have been used for connecting saw-blades to their handles; but such cast-metal frames are heavy and expensive, while my sheet-metal frame is very light and cheap, and, in addition thereto, it has the great advantage that its arms b b', being flexible, can be readily bent to accommodate themselves to the edges of the handle, and the jaws c c', being also flexible, are drawn close up by the rivets h against the opposite sides of the blade, so that a firm, durable, light, and cheap connection for the saw-blade with its handle is obtained. The jaws of the sheet-metal frame, being flexible, are capable of yielding laterally, whereby saw-blades of varying thickness at the butt-end can be introduced between the jaws and there confined by drawing the jaws upon the blades by the rivets. By the spur a the tail of the blade is held steady. If desired, the slot d in the frame D may be extended, so as to admit the back edge of the tail C and to steady said tail during the operation of sawing.

What I claim as new, and desire to secure by Letters Patent, is—

1. A frame for connecting a handle with a saw-blade, composed of a single piece of sheet metal bent to form the upper and lower flexible arms, b b', and the two parallel flexible jaws c c', said arms being capable of bending to conform to the upper and lower edges of the handle, and the jaws capable of yielding laterally to receive between them saws of varying thickness, substantially as described.

2. The combination, with a handle, B, and a saw-blade, A, of the sheet-metal frame D, formed integral with the upper and lower flexible arms, b b', bent to conform with and attached to the upper and lower edges of the handle, and the flexible jaws c c', capable of yielding laterally and clamped upon the butt-end of the saw-blade, substantially as described.

3. The combination, with a saw-handle and a slotted frame attached thereto, of a saw-blade having its butt-end secured in the slot of the frame, and constructed with a tail, C, extending back of the butt-end of the blade and supported against the handle, substantially as described.

4. The combination, with a saw-handle, of a saw-blade having its butt-end connected with

the handle, and constructed with a tail extending back of the butt-end of the blade and supported by the handle, substantially as and for the purpose described.

- 5 5. The combination of a handle, B, and a sheet-metal frame, D, constructed with upper and lower flexible arms, $b b'$, bent to conform with and secured to the upper and lower edges of the handle, and with two flexible jaws, $c c'$, capable of yielding laterally, with a saw-blade, A, having its butt-end secured between the jaws, and constructed with a tail, C, extending back of the butt-end of the saw-blade and supported by the handle, substantially as described.
- 10 6. The combination of a handle, B, and a sheet-metal slotted frame, D, having the flexible arms $b b'$ and flexible jaws $c c'$, with the saw-blade having its butt-end secured between the jaws, and constructed with a tail, C, ex-

tending back of the butt-end of the blade and 20 entering the slot in the frame, said tail being supported by the handle, substantially as described.

7. The combination of a handle, B, and a frame, D, having flexible arms $b b'$ and flexible jaws $c c'$, with a saw-blade, A, having its butt-end secured between the jaws, and constructed with a tail, C, extending back of the butt-end of the blade, and provided with a spur, a, entering the handle, substantially as 25 described.

In testimony whereof I have hereunto set my hand and seal in the presence of two subscribing witnesses.
